CHAIR LEG REST

Albert L. Beisel, Shohola, Pa.

Application May 2, 1935, Serial No. 19,503

5 Claims. (Cl. 45—137)

This invention relates to a rest for use on the rear legs of chairs to facilitate movement of the chair to an inclination without indenting, marring, or injuring the floor surface, rug, or other covering. Many people have a habit of leaning back in a chair, and it is for the protection of the floor or covering when so used, that the present invention has been devised.

It is particularly aimed to provide an exceedingly simple, durable and inexpensive construction capable of ready attachment.

The more specific objects and advantages will become apparent from a consideration of the description following taken in connection with accompanying drawing illustrating an operative embodiment.

In said drawing:

Figure 1 is a side elevation of a chair having both rear legs equipped with my improvement;

Figure 2 is a side elevation of a chair leg equipped with my improvement;

Figure 3 is a rear elevation of a chair leg equipped with my improvement;

Figure 4 is a vertical sectional view taken on the line 4—4 of Figure 3;

Figure 5 is a vertical sectional view taken on the line 5—5 of Figure 2; and

Figure 6 is a horizontal sectional view taken on the line 6—6 of Figure 2.

Referring specifically to the drawing, a conventional chair is shown at 10, the rear legs of which are specifically designated 11. The rest, generally designated 12 is adapted to be attached, one at the lower end of each of the rear legs 11, such legs being shortened, if necessary, so that the seat of the chair will be level.

The improved device 12 comprises a base section 13, preferably metallic, having a flat bottom portion 14 and parallel upwardly extending ears 15, integral therewith and arranged at opposite sides thereof. An upper section 16 has a flat portion 17 disposed across the lower end of the leg 11 and secured thereto by means of a screw or other fastening 18, which it will be noted is vertical or at an angle to the general direction of the leg 11 for a more secure attachment. The section 17 also has an integral tongue 19 at the rear, in contact with the legs and secured thereto adjacent the top by means of a screw or other fastening 20.

Said portion or plate 17 has diametrically extending lugs 21 which are disposed in arcuate slots 22 formed in the ears 15.

As a result of the construction described, the chair may be tilted or rocked from the full line to the dotted line position suggested in Figures 1 and 2 with the section 13 remaining stationary

and flat on the floor, and with the section 19 fulcruming relatively thereto at the junction of the plate 17 and tongue 19, since the lugs 21 will move within the slots 22.

It will be noted that the portion 14 has an opening 23 therethrough. Such opening enables screw 18 to be applied and a tool to be engaged therewith in applying and removing such screw.

Various changes may be resorted to provided they fall within the spirit and scope of the invention.

What is claimed is:

1. A device of the class described having a base section adapted to rest on a floor, a section pivoted thereto and attachable to a chair leg by a driven fastening therethrough and into the leg end, the first mentioned section having an opening therethrough to align with said driven fastening in one position of the two sections to permit moving said driven fastening relatively to the leg.

2. A device of the class described having a floor-engaging portion, a portion attachable to a leg and rockably supported on said floor engaging portion, lugs on one of said portions, and the other portion provided with arcuate slots engageable by said lugs to pivotally secure said portions together.

3. A device of the class described comprising a floor-engaging plate, ears rising from said plate provided with arcuate slots, a plate attachable against the lower end of a chair leg, said plate being adapted to fulcrum on the first mentioned plate and having lugs disposed and operable in said slots.

4. A device of the class described comprising a floor-engaging plate, ears rising from said plate provided with arcuate slots, a plate attachable against the lower end of a chair leg, said plate being adapted to fulcrum on the first mentioned plate and having lugs disposed and operable in said slots, the first mentioned plate having an opening therethrough permitting access to fastening means for the second mentioned plate.

5. A device of the class described comprising a floor-engaging plate, ears rising from said plate provided with arcuate slots, a plate attachable against the lower end of a chair leg, said plate being adapted to fulcrum on the first mentioned plate and having lugs disposed and operable in said slots, the first mentioned plate having an opening therethrough permitting access to fastening means for the second mentioned plate, and a tongue integral with the second mentioned plate attachable to the chair leg.
